UNITED STATES PATENT OFFICE.

WILLIAM PAINTER, OF BALTIMORE, MARYLAND, ASSIGNOR OF ONE-HALF
TO LEWIS R. KEIZER, OF SAME PLACE.

BOTTLE-STOPPER.

SPECIFICATION forming part of Letters Patent No. 324,040, dated August 11, 1885.

Application filed April 9, 1885. (No model.)

To all whom it may concern:

Be it known that I, WILLIAM PAINTER, of Baltimore, Maryland, have invented a new and useful Improvement in Bottle-Stoppers; 5 and I do hereby declare that the following is a full and accurate description of the same.

Elastic stoppers wholly of vulcanized rubber, or with a rubber shell covering a metal core, are in common use; but such stoppers 10 are unsuited for many uses where elastic stoppers would be desirable, by reason of the disagreeable taste and odor imparted to the contents of the bottle by the rubber, and also of the corrosive and destructive action of the 15 contents upon such stoppers.

The principal object of my invention is to provide an elastic stopper with a rigidly-attached, flexible, yielding, non-metallic protective coating interposed between the rubber stopper and the contents of the bottle, of 20 such nature as not to affect said contents, and at the same time to resist their corrosive action.

Heretofore stoppers of rubber, as well as of cork and other materials, have been provided 25 with a protecting non-oxidizable covering of metal foil to isolate them from the inclosed liquids; but such a covering is very different from my invention. A metal coating will not readily conform to the inequalities of surface 30 which the elastic stopper conforms to with ease. When a stopper coated with foil is forced into a bottle, the foil does not yield as a mass, as the elastic stopper itself does, but by wrinkling and puckering, failing thereby 35 to make a perfectly-tight joint. It is, moreover, very liable to rupture, is not durable enough for continuous use, and difficult to firmly attach to a rubber stopper. For these and other reasons it is not well adapted to the 40 purpose.

I am also aware that india-rubber stoppers have been coated with "flock;" but such coating, although fibrous, is incapable of holding 45 a body of neutral paraffine to isolate the rubber from the liquid within the vessel. I am also aware that a wooden bung or stopper has had its end saturated with paraffine to prevent the escape of gases through the pores of the wood. This is different both in structure and capacity for use from my invention. 50 I am also aware that with a vessel of

wood lined with pitch it has been proposed to employ a cork covered with paraffine, to prevent it from sticking to the pitch; but this is not my invention, because it does not possess the means required to hold a sufficient quantity of paraffine to be effective for the purpose described by me. 55

My invention obviates these defects; and it consists, mainly, in permanently attaching to 60 a rubber or other elastic stopper a cover or coating of some fibrous or textile material saturated or coated with some neutral substance—such as paraffine or other resistant body not capable of affecting or being affected by the 65 contents of the bottle.

The protecting-covering may envelop wholly or only partly that portion of the stopper within the mouth of the bottle, or it may be applied to the inner end of the stopper as a 70 disk of the same or a little greater diameter as the stopper itself, the disk in this case forming virtually part of the body of the stopper.

For such stoppers as are employed in bottling beer, mineral-water, &c., and which are used many times, it is important that the protecting-coating may be attached very firmly 75 to the stopper.

Owing to the non-adherent property of rubber very few substances will attach themselves strongly to it in the process of vulcanization; but textile or fibrous materials—such as cotton canvas, cloth, felt, &c.—can, by well-known processes, be very firmly united 80 to the rubber during vulcanization. In practice I find this the best and cheapest means of attaching the fibrous material to the rubber, and prefer to vulcanize one or more layers or disks of cotton canvas directly on the inner 85 end of the stopper; and then saturate the fabric with paraffine or other neutral resistant substance. 90

In the drawings, Figure 1 is a section of a rubber stopper having the protecting coating 95 attached to its end in disk form; Fig. 2, a section of a similar stopper having the coating in cup form.

The invention is illustrated as applied to an ordinary beer-bottle stopper. 100

In Fig. 1, A is the metal button, and B the rubber stopper. C is a disk formed of one or

more layers of cotton canvas, woolen cloth, felt, or other fibrous material to which the rubber will firmly adhere.

I find it expedient to use two or three layers 5 of comparatively thin canvas to obtain the necessary thickness, rather than one piece of very heavy material, for the reason that with the finer and thinner fabric there is less disposition to ravel or fluff out.

10 The several layers of canvas are first united by a very thin coating of vulcanized rubber, and disks of proper size are then cut out of the sheet and placed in the molds in which the stoppers are formed and vulcanized.

15 During the vulcanizing process the cotton disk is solidly attached to the rubber stopper. The outer surface of the fibrous disk is not coated with the rubber, nor does the rubber penetrate the body of the canvas. We have 20 therefore a practically solid mass of cotton of one-eighth of an inch (more or less) in thickness at the end of the stopper, sufficient when saturated, to completely isolate the rubber from the inclosed liquid.

25 Fig. 2 shows a fibrous covering of cotton canvas of cup form, inclosing the end and lower portion of the stopper and vulcanized directly to it. In both these cases the canvas is finally saturated with melted paraffine and 30 the stoppers are then ready for use. Other substances may be used to saturate the absorbent coating—as, for instance, shellac dissolved in alcohol. Various other gums, resins, and resistant materials, (neutral as to the in-

35 closed liquid,) melted or in solution, may also be applied to the fibrous covering; but I regard paraffine as the best, because of its tasteless, odorless, and highly-resistant properties.

40 Instead of saturating the canvas it may be coated with some protecting material—such as dissolved or melted gutta-percha—which, while not actually penetrating the body of the canvas, will adhere firmly to its surface.

45 By using cotton canvas and vulcanizing it directly to the rubber I attain excellent results, because the union of the two materials is firm and solid, the canvas at the same time being well adapted to absorbing or retaining

50 as a coating any protective substance that it may be desirable to use. The function of the fibrous coating is, therefore, that of a medium for firmly uniting the protecting materials to the stopper. The rubber, canvas, and resist-

55 ant substances are therefore practically homologous.

I have described a fibrous coating vulcanized directly to the rubber, because that pro-

cess gives the best results; but it is practicable to cement or otherwise permanently attach 60 such covering to the stopper after vulcanization, and saturate or coat it as before described.

Aside from its non-corrodible and protecting qualities, a stopper having a fibrous covering saturated with paraffine, as described, 65 is much more durable than one entirely of rubber, because the canvas will withstand more wear.

Stoppers so made can be used of considerably larger size (with respect to the size of the 70 bottle-mouth) than would be practicable if made wholly of rubber, because the lubricating nature of the paraffine coating greatly facilitates the entrance of the stopper. A much more secure closure of the bottle is thereby 75 effected. The saturated disks (or the fibrous coating of cup form, when it is used) readily conform to the varying sizes and irregularities of bottle-mouths, yielding and adapting 80 itself thereto and fitting as closely and making as tight a closure as though the stopper were wholly of rubber. This is important in effecting a complete isolation of the rubber from the inclosed liquid. Inasmuch as the 85 cotton disk, when saturated with paraffine, is quite yielding, it may, as before stated, be made slightly larger than the body of the stopper, so as to insure a close tight fit.

While I prefer to apply the neutral protecting substance to the fibrous coating after it 90 has been attached to the stopper, it is not always necessary to do so. In some cases it may be applied before.

It is evident that various forms of rubber and other elastic stoppers, including those in 95 the forms of disks, rings, &c., for fruit-jars and other purposes, may be coated and protected in the manner described, and I do not therefore limit myself to those herein described.

100 I claim as new—

1. An elastic stopper combined with a rigidly-attached covering of some fibrous material saturated or coated with a neutral substance—such as paraffine or some other resistant body—substantially as and for the purpose set forth.

2. An elastic rubber stopper having a covering of some fibrous material vulcanized thereto and saturated or coated with some neutral non-corrodible body, substantially as and for the purpose set forth.

110 WILLIAM PAINTER.
